(57) **CLAIM**

The ornamental design for a full LED daytime running lamp grille, as shown and described.

DESCRIPTION

FIG. 1 is a front, top, right perspective view of a full LED daytime running lamp grille, showing the claimed design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

Shading is used to illustrate the curvature of the part and not color. The claimed design is indicated by the relatively dark portions in the drawings, while the relatively light portions are environmental and form no part of the claimed design.
